W. HEIDINGER

CARD STRIPING DEVICE

Filed Sept. 14. 1923

Invenio
Willy Heidinger

By his Attorneys
Cooper, Kerr & Dunham.

UNITED STATES PATENT OFFICE.

WILLY HEIDINGER, OF BERLIN, GERMANY, ASSIGNOR TO THE TABULATING MACHINE COMPANY, OF ENDICOTT, NEW YORK, A CORPORATION OF NEW JERSEY.

CARD-STRIPING DEVICE.

Application filed September 14, 1923. Serial No. 662,630.

To all whom it may concern:

Be it known that I, WILLY HEIDINGER, a citizen of the Republic of Germany, residing at Berlin, Germany, have invented certain new and useful Improvements in Card-Striping Devices, of which the following is a full, clear, and exact description.

This invention relates to card striping or inking devices.

Where large numbers of cards are used, as for instance, in connection with tabulating machines or other business machines, it is sometimes desirable to provide distinguishing marks upon the cards of separate groups or of some particular groups, so that the mere sight of a card will reveal the group to which it belongs; or, should a card belonging to one group be inadvertently placed in a wrong group, it will be readily detected by an operator who is running the cards through a machine or otherwise handling them. Also it will be seen that cards so marked are less apt to be placed in wrong groups.

The use of cards cut from stock of different colors for separate groups has been commonly practiced, but this method is an expensive one and necessitates keeping a large variety of stock on hand from which to produce the cards.

Numerous methods may be employed for applying distinctive markings to groups of cards cut from uniform stock. Ordinarily, however, such methods are apt to be too complicated and to require too much machinery, and are therefore prohibitive.

According to my invention, a stripe of any desired color may be drawn, preferably across the top of the card, and the apparatus employed is very simple and inexpensive.

Referring to the drawings wherein I have shown what I now consider to be the preferred form of my invention:

Fig. 1 is a sectional side elevation of the apparatus showing the manner in which the ink is applied to the card stock as it is being unwound from the roll.

Fig. 2 is a fragmentary plan view of a part of Fig. 1.

Fig. 3 is a view of a card which has had a colored stripe applied thereto in accordance with my invention.

Referring more specifically to the drawings, 1 represents an ink reservoir having

an air-tight stopper 2 in the top thereof, and an air tube 3 reaching through said stopper and to the lower part of the reservoir. The upper and outer end of the tube may be bent over as shown to prevent its passage from becoming clogged by particles of dust. Near the bottom of the reservoir is another opening closed by a stopper 4 having a tube 5 communicating with the interior of the reservoir. The tube 5 arches over the side of a small container 6 in the manner of a siphon and reaches down into said container; a wick 7 of felt or other suitable material reaches upwardly in the container 6 and emerges through a channel member 8, having an adjusting device 9 similar to the well known wick-feeding devices used in oil lamps.

In the production of cards to be used in connection with tabulating machines, the stock is usually provided in long strips the width of the cards and wound upon a reel. The stock is then fed from the reel into the printing press where blank card forms are printed upon it and where it is cut into card lengths.

In the drawings the roll of stock is shown at 10, being fed as at 11 between guide rollers 12 into the printing press. The reservoir 1 and container 6 may be mounted on a support 13 which may be a fixed part of the printing press or a shelf fixedly attached to the press. Any suitable attaching means 14 may be provided for securing the container to the support. Such means may be adjustable if desired so that the distance between the container and the paper may be varied. When the parts are in position with the end of the wick 7 adjacent the surface of the paper the final adjustment for controlling the degree of pressure of the wick upon the paper will be made through the device 9.

In operation it will be seen that with both ends of tube 3 open, the level of the liquid in the tube will be controlled by the liquid level in container 6. As the level in said container is lowered by consumption and becomes lower than the lower end of tube 3, air will leak through tube 3 into the reservoir and rise to the top thereof. This will permit a flow of liquid thru tube 5 to container 6 until the liquid level therein is again the same as the end of the tube 3. The ink level in container 6 may be fixed by

raising or lowering the tube 3 by sliding it through the stopper 2. The end of tube 5 in container 6 should be lower than that of tube 3 in the reservoir 1, so that the level in the container will not fall below the end of the tube 5 and permit air to become trapped therein and stop the flow of ink.

With the wick 7 touching the paper 11, it will be seen that as the paper is drawn into the press a band of ink will be applied as at 15, Fig. 2.

In Fig. 3, the card 16 is shown with the band of ink across the top.

Having described my invention, what I claim and desire to secure by Letters Patent is:

1. In an ink applying device, an ink reservoir, an ink container connected with said reservoir adjacent the lower end of the latter to receive ink therefrom, a wick associated with said container for absorbing and applying the ink, and an air inlet for said reservoir for controlling the flow of ink therefrom to said container.

2. In an inking device, a reservoir, an ink container, means connected adjacent the bottom of the reservoir for transferring ink to the container, and an air tube associated with said reservoir and independent of the aforesaid connecting means to said container for controlling the transfer of ink from the reservoir to said container.

3. In combination, in an ink applying device including means for feeding paper, an ink container having a wick adapted to en-

gage the paper being fed for applying ink thereto, a reservoir adapted to supply ink to said container and hydrostatic control means for regulating the flow of ink from said reservoir to said container.

4. In combination, in an ink applying device including means for feeding paper, an ink container having a wick adapted to engage the paper being fed for applying ink thereto, means for adjusting said wick, a reservoir adapted to supply ink to said container and adjustable hydrostatic control means for regulating the transfer of the ink.

5. In an inking device, a plurality of containers interconnected for the transfer of ink, an ink applying element associated with one of said containers, and means including an adjustable air inlet tube associated with the supply containers and independent of the discharging interconnection to the other container.

6. In an inking device, a reservoir, a container, a tube connected with the lower portion of said reservoir and arching over the side of said container and dipping into the same, a second tube connected with said reservoir for supplying air thereto and being adapted to control the air pressure in the reservoir in accordance with amount of ink in said container.

In testimony whereof I hereto affix my signature.

WILLY HEIDINGER.
